UNITED STATES PATENT OFFICE.

JOHN L. QUINN, OF LOS ANGELES, CALIFORNIA, ASSIGNOR TO STANDARD OIL COMPANY, OF RICHMOND, CALIFORNIA, A CORPORATION OF CALIFORNIA.

DESIGN FOR A SIGN.

47,965.

Specification for Design.

Patented Oct. 12, 1915.

Application filed March 25, 1915. Serial No. 17,078. Term of patent 3½ years.

To all whom it may concern:

Be it known that I, JOHN L. QUINN, a citizen of the United States, residing at the city and county of Los Angeles, State of California, have invented a new, original, and ornamental Design for Signs, of which the following is a specification, reference being had to the accompanying drawing, forming a part thereof.

The figure is a plan view of a disk showing my new design.

I claim:

The ornamental design for a sign as shown.

J. L. QUINN.

Witnesses:

A. HANILL,

R. L. WERNER.
